CLAIM

The ornamental design for an ice skate, as shown and described.

DESCRIPTION

FIG. 1 is a rear perspective view of an ice skate showing our new design;

FIG. 2 is a right side view thereof;

FIG. 3 is a left side view thereof; and,

FIG. 4 is a rear view thereof.

The broken line showing of the remainder of the ice skate is for illustration purposes only and forms no part of the claimed design.
